KNIFE HANDLE

Alessandro Rosa Fauzza, Via Manzoni 2,
Maniago, Pordenone, Italy

Filed Aug. 2, 1972, Ser. No. 277,313

Term of patent 3½ years

Int. Cl. D7—03

U.S. Cl. D7—152

FIG. 1 is a side elevational view of a knife handle showing my new design;

FIG. 2 is a top edge view thereof; and

FIG. 3 is a bottom edge view thereof.

The side opposite that shown in FIG. 1 is substantially a mirror image of the side shown in FIG. 1.

I claim:

The ornamental design for a knife handle, as shown and described.
